CLAIM

The ornamental design for a golf ball, as shown and described.

DESCRIPTION

FIG. 1 is a front side view of a new design for a golf ball, according to a first embodiment;

FIG. 2 is a rear side view of the golf ball shown in FIG. 1; FIG. 3 is a left side view of the golf ball shown in FIG. 1; FIG. 4 is a right side view of the golf ball shown in FIG. 1; FIG. 5 is a top view of the golf ball shown in FIG. 1; FIG. 6 is a bottom view of the golf ball shown in FIG. 1; FIG. 7 is a side perspective view of the golf ball shown in FIG. 1;

FIG. 8 is a front side view of a new design for a golf ball, according to a second embodiment; and

FIG. 9 is a rear side view of the golf ball shown in FIG. 8; FIG. 10 is a left side view of the golf ball shown in FIG. 8; FIG. 11 is a right side view of the golf ball shown in FIG. 8;

FIG. 12 is a top view of the golf ball shown in FIG. 8; FIG. 13 is a bottom view of the golf ball shown in FIG. 8; and,

FIG. 14 is a side perspective view of the golf ball shown in FIG. 8.

The broken line showing of a golf ball surface and printed golf ball name in the first and the second embodiments, are included for the purpose of illustrating environmental subject matter and form no part of the claimed design. The broken lines showing of printed horizontal lines and an arrow in the second embodiment depict portions of the golf ball that forms no part of the design.
